SIFTER TOP

Filed April 25, 1946

UNITED STATES PATENT OFFICE

2,472,520

SIFTER TOP

Allen B. Criss, Biloxi, Miss.

Application April 25, 1946, Serial No. 664,841

1 Claim. (Cl. 65—57)

1

This invention relates to new and useful improvements and structural refinements in sifter tops, and the principal object of the invention is to provide a device of the character herein described, such as may be effectively and conveniently employed in association with condiment shakers and the like, for the purpose of dispensing the contents thereof.

The device is particularly intended for use with salt shakers, to eliminate the previously experienced inconvenience resulting from the sifter openings of the conventional shakers becoming clogged or otherwise obstructed, during moist weather.

A further object of the invention is to provide a sifter top which may be readily applied to or removed from the condiment receptacle associated therewith.

An additional object of the invention is to provide a sifter top which may be readily employed with condiment shakers or receptacles having various sizes and forms.

A still further object of the invention is to provide a sifter top which is simple in construction and operation, and which will readily lend itself to economical manufacture.

With the above more important objects in view, and such other objects as may become apparent as this specification proceeds, the invention consists essentially of the arrangement and construction of parts as illustrated in the accompanying drawings, in which:

Figure 1 is a perspective view illustrating a portion of the condiment shaker and showing the invention in situ thereon;

Figure 2 is a top plan view of the invention per se;

Figure 3 is an underside plan view of the same;

Figure 4 is a side elevation thereof;

Figure 5 is a cross sectional view, taken in the plane of the line 5—5 in Figure 2;

Figure 6 is a perspective view illustrating an agitator used in the invention, and

Figure 7 is a perspective view of a modified agitator.

Like characters of reference are used to designate like parts in the specification and throughout the several views.

Referring now to the accompanying drawings in detail, the invention embodies in its construction a sifter top designated generally by the reference character 10, the same consisting of a cap 11, configurated substantially as shown and adapted for removable attachment to the condiment shaker 12.

2

The cap 11 may, of course, be constructed of any suitable material and the general configuration thereof should blend, more or less, with the design and styling of the condiment shaker. If the latter is provided with a screw-threaded mouth, the open end of the cap 11 may be internally threaded as at 13, for obvious reasons.

The cap 11 is provided with a substantially flat surface 14, this in turn being formed with a plurality of spaced parallel slots 15. These slots, in effect, constitute the sifter opening, the action thereof being hereinafter more fully set forth.

The agitator designated generally by the reference character 16 comprises a plate 17, this being angulated at the relatively opposite edges thereof to form a pair of outer ribs 18. A plurality of prongs 19, which for purposes of consistency will be hereinafter referred to as the inner ribs, are provided also on the plate 17, intermediately of the outer ribs 18.

The plate 17 is slidably positioned on the outer surface of the cap portion 14, with the ribs 18 and 19 extending through the respective slots 15. The outer ribs 18 are, in turn, provided with the inturned flanges 20, these being disposed adjacent the inner surface 21 of the cap portion 14 and effectively functioning to retain the agitator 16 as a whole, in position on the cap 11.

The outer surface of the plate 17 is provided with an upraised portion 22, this in turn, being formed with a concave recess 23. It will be noted that this recess will function as a convenient finger catch, for sliding the agitator 16.

When the invention is placed in use, the sifter 35 top 10 is, of course, applied to the condiment shaker 12, whereupon the agitator 16 may be slid to and fro in the slot 15, as indicated by the phantom lines 24 in Figure 4. It will be apparent that in this manner, the contents of the shaker 40 will be prevented from clogging of otherwise obstructing the sifter openings.

Referring now to the accompanying Figure 7, the agitator designated generally by the reference character 25 may be employed in substitution for the agitator 16. The agitator 25 is formed from one piece of material such as a metal stamping, and consists of a substantially rectangular sheet or plate 26, this being slotted to provide a pair of spaced, longitudinally aligned ribs 27 at 50 each of two relatively opposed edges of said plate.

The mid-portion 28 of the plate 26 between each aligned pair of the ribs 27 are arcuated and overlapped one over the other, to constitute a finger catch 29. The portions of the remaining edges of 55 the plate 26 are notched and angulated to provide

further prongs or ribs 30, intermediately of the ribs 27. It should be understood that the agitator as shown in Figure 7 is partially broken away to reveal its construction, and actually, the rib 27 which is shown broken away, should extend as 5 illustrated by the phantom line 31.

The agitator 25 is used in the same manner as the aforementioned agitator 16, that is, with the plate 26 being slidably positioned on the sifter cap, and the ribs 27 and 30 extending through the 10 sifter openings. It will be noted that the outer ribs 27 are angulated to provide the inturned retaining flanges 32, the function of which is similar to that of the flanges 20.

It is believed that the advantages and use of the invention will be clearly understood from the foregoing disclosure and accordingly, further description thereof at this point is deemed unnecessary. 15

While in the foregoing there has been shown and described the preferred embodiment of this invention it is to be understood that minor changes in the details of construction, combination and arrangement of parts may be resorted to without departing from the spirit and scope 25 of the invention as claimed.

What I claim as my invention is:

A sifter top comprising a cap having a flat upper wall and sloping side walls leading to the upper wall, said upper wall having a plurality of 30

spaced parallel slots, and an agitator comprising a plate formed from one rectangular sheet of material, said plate being slotted to provide a pair of spaced longitudinally aligned ribs at each of two relatively opposed edges of said plate, the mid-portions of said plate between said ribs being arcuated and overlapped one over the other to constitute a finger grip, portions of the remaining edges of said plate being notched and angulated to provide further ribs intermediately of said first mentioned ribs, said plate being slidably positioned on the outer surface of the upper wall, said ribs extending through said slots, and said first mentioned ribs being angulated and forming inturned retaining flanges frictionally engaging the inner surface of the upper wall. 15
